DESIGN FOR A WASHING MACHINE FOR DISHES AND GLASSES

Libero Palmieri, New York, N. Y.

Application March 31, 1942, Serial No. 106,411

Term of patent 14 years

To all whom it may concern:

Be it known that I, Libero Palmieri, a citizen of the United States of America and a resident of the county of New York, city and State of New York, have invented a new, original, and ornamental Design for a Washing Machine for Dishes, and Glasses, of which the following is a specification, reference being had to the accompanying drawings forming a part thereof.

On the drawings:

Figure 1 is a top plan view of a washing machine for dishes and glasses showing my new design.

Figure 2 is a front view in elevation of the same.

Figure 3 is a side view in elevation taken from the right of Figure 1.

Figure 4 is a side view in elevation taken from the left thereof.

I claim:

The ornamental design for a washing machine for dishes and glasses, as shown.

LIBERO PALMIERI.
